US00D635971S

(12) **United States Design Patent** (10) **Patent No.:** **US D635,971 S**
Sip et al. (45) **Date of Patent:** **** Apr. 12, 2011**

(54) **PORTABLE DEVICE**

(75) Inventors: **Kim-Yeung Sip**, Shenzhen (CN);
Feng-Xiang Tang, Shenzhen (CN)
(73) Assignee: **Hon Hai Precision Industry Co., Ltd.**,
Tu-Cheng, New Taipei (TW)

(**) Term: **14 Years**

(21) Appl. No.: **29/342,269**

(22) Filed: **Aug. 20, 2009**

(30) **Foreign Application Priority Data**

Mar. 2, 2009 (CN) 2009 3 0300932

(51) **LOC (9) Cl.** **14-02**

CLAIM

The ornamental design for portable device, as shown and described.

DESCRIPTION

FIG. 1 is a perspective view of a portable device showing our design; and,

FIG. 2 is a front elevational view thereof.

The portions of the portable device shown in broken lines form no part of the claimed design.

1 Claim, 2 Drawing Sheets

FIG. 1

FIG. 2
